SORTING APPARATUS

John H. Bloom and Orin D. Channer, both of Springfield, Oreg., assignors to Vancouver Plywood Co., Vancouver, Wash., a corporation of Washington

Filed Jan. 18, 1962, Ser. No. 167,116

4 Claims. (Cl. 198—105)

This invention relates to sorting apparatus, and more particularly to apparatus for sorting articles such as veneer sheets into piles determined by width, moisture content, grade, etc. The apparatus of the invention is characterized by a number of novel features making it preferable to the usual prior known types of sorters.

In the sorting of articles such as veneer sheets traveling from a clipper, there are a number of factors that must be considered if the apparatus performing the sorting is to perform satisfactorily. For one thing, veneer sheets frequently are traveling from the clipper in a steady flow and at a relatively fast rate, and thus any sorting apparatus used must be fast and accurate in its operation. Further, veneer often is fragile, and is easily broken if not handled properly, and thus the veneer cannot be subjected to too rough handling. Additionally, veneer may be quite thin, and some provision should be made to prevent veneer sheets from becoming misshapened in such a manner as to hamper sorting. Considering certain practicalities, the usual veneer plant is relatively crowded, and any apparatus provided for sorting should be as compact as possible. Also important, it is desirable that sheets after they have been sorted be easily stacked in an orderly manner.

Generally, it is an object of this invention to provide sorting apparatus that takes care of the problems hereinabove indicated in a highly satisfactory and practical manner.

More specifically, it is an object of this invention to provide improved sorting apparatus, that includes conveyer means for transporting pieces such as veneer sheets along an elongated path with such pieces traveling in a direction extending transversely of their length, and means for ejecting pieces of veneer traveling on the conveyer means laterally, either to one side or the other of the path of the conveyer means, and into appropriate piles. In a preferred embodiment of the invention, it is contemplated that plural sorting stations be provided along the length of the conveyer means, and that each sorting station be provided with a pair of ejector means or mechanisms. One is used to eject sheets to one side of the path of the conveyer and one is used to eject sheets to the other side of the path of the conveyer. With the apparatus contemplated, there is a minimum amount of handling of the veneer sheets prior to their removal. The sheets travel in a straight path during the sorting, with such path being a continuation of the path of travel of veneer through a clipper. Removal of veneer sheets from the conveyer may be speedily done, and with suitable control means provided the sorting can be substantially automatic.

Another object of the invention is to provide, in a sorting line, a sorting station which features a pair of ejector means or mechanisms, one for ejecting a sheet or article to one side of the sorting line and one for ejecting a sheet

2

to the other side, wherein each ejector means comprises a pair of pinch rollers normally occupying an inoperative position (where their surfaces are above and below the surfaces of sheets in the station). Upon actuation, at least one (preferably both) of the pinch rollers of an ejector means moves to a position to grab the end of a sheet in the station, and with the roller rotating this starts its travel laterally to one side of the sorting line. Also included in each ejector means or mechanism are a pair of pinch rollers spaced beyond the ends of sheets traveling on the conveyer. These rollers receive sheets whose travel to one side has been started by the first-mentioned pair of pinch rolls. In other words, one set of pinch rollers feed the other set, and the second set is relied upon to throw a sheet clear of the conveyer. Preferably the second set of pinch rollers are close enough to the first set so as to engage an end of a veneer sheet prior to its other end leaving the first set of rollers. This makes for more positive removal.

Since movement of veneer sheets off the conveyer is with the sheets traveling in the direction of their length, the veneer sheets are ejected while moving in a direction parallel to their grain. This is advantageous since on being received in a stack the veneer sheets are positioned in a manner best able to withstand breaking or fracture. Sorting of veneer sheets is done to both sides of the conveyer, as this enables two sorting operations to be performed in one sorting station.

Objects and advantages other than those enumerated above are attained by the invention, and such will become more fully apparent as the following description is read in conjunction with the accompanying drawings, wherein:

FIG. 1 is a drawing, somewhat simplified, illustrating a processing line in a veneer plant, and showing a clipper station and a number of sorting stations at succeeding intervals along the line, whereby veneer cut in the clipper and traveling down the line may be sorted as to grade, width, etc.;

FIG. 2 is a side elevation of a sorting station as contemplated by the invention, with portions broken away;

FIG. 3 is a cross-sectional view, taken generally along the line 3—3 in FIG. 2, and with portions broken away, further illustrating the sorting station shown in FIG. 2;

FIG. 4 is an end elevation of portions of the apparatus illustrated in FIG. 2, taken generally along the line 4—4 in FIG. 2; and

FIG. 5 is a view, taken generally along the line 5—5 in FIG. 3, and on somewhat an enlarged scale, illustrating an adjustable stop means that is part of the apparatus illustrated.

Referring now to the drawings, and first of all with particular reference to FIG. 1, a processing line such as may be provided in a veneer plant is illustrated. The line includes an elongated conveyer means, indicated generally at 10, for transporting veneer sheets or pieces along a path, with the sheets traveling in a direction extending transversely of their length. Conveyer means 10 includes adjacent the feed end a section 10c, and separates into two branches after section 10c, indicated at 10a and 10b, with branch 10a superimposed over branch 10b. Provided at intervals along the length of conveyer means 10, more specifically its branches, are a series of sorting stations, represented by the block outlines indicated at 12, 14, 16, and 18. As will hereinafter be described, in these sorting

stations veneer sheets traveling down the conveyer means may be removed, and thence ejected laterally to one side of the conveyer means.

Adjacent the feed end of the processing line illustrated is a clipper, represented by the block outline indicated at 20. In the clipper, veneer is cut into sheets as desired. Feeding the clipper is a conveyer 22. Conveyer means 10 of the sorting line is aligned longitudinally with conveyer section 22, and defines a path for veneer pieces that is a continuation of the path for veneer fed the clipper defined by section 22.

Veneer pieces or sheets flowing from the clipper are of random grade, width, moisture, etc. Upon leaving the clipper, the sorting stations are used to produce stacks of veneer sheets of like grade, width, moisture, etc.

On the feed side of clipper 20 is a control station, indicated generally by the block outline 24. An operator in the control station may actuate suitable control means, whereby veneer on reaching the clipper is clipped into sheets of desired widths (determined by visual inspection made at the control station 24). The clipper blade extends transversely of conveyer 22, so that with the blade actuated rapidly in succession, a narrower piece results than when successive actuations of the blade occurs over a longer interval. As contemplated by this invention, the operator at the control station 24 may also actuate suitable mechanism controlling the actuation of stations 12-18, such mechanism, ordinarily including some sort of a memory circuit, so that when a veneer sheet comes to a sorting station, it will be removed from the conveyer means depending upon the selection made by an operator at station 24.

A processing line, such as may be provided in a veneer plant to follow a veneer clipper, has so far been described only generally. Reference is now made to FIGS. 2, 3, 4, and 5, where portions of the processing line, and one of the sorting stations (namely station 12) are illustrated in more detail.

As can be seen with reference to these figures, section 10c and branches 10a, 10b of conveyer means 10 may each comprise a series of laterally spaced belts, as exemplified by belts 26 of branch 10b (best shown in FIG. 2). The belts have upper runs extending in elongated horizontal reaches, and the ends of the belts are trained over suitable pulleys, such as pulley 28. A suitable motor means is provided (not shown), for rotating the belts of branches 10a, 10b, and section 10c, whereby those portions of the belts that engage veneer pieces move from left to right in FIG. 2, so that they are operable to transport the veneer pieces in the same direction.

Forming the feed end of branch 10a is a tipple conveyer section 30. Also part of branch 10a, and on the off-bearing side of section 30, is a conveyer section 32. In the embodiment of the invention shown, it is the latter section that actually transports veneer pieces or sheets through sorting section 12. Supporting tipple conveyer section 30 and conveyer section 32, and branch 10b beneath the sections, is a suitable frame 34. The tipple conveyer section may be swung between the lowered position, illustrated in dashed outline in FIG. 2, and the raised position, illustrated in solid outline. When raised, it is operable to direct veneer sheets traveling on section 10c, and direct them upwardly to upper branch 10a.

Tipple conveyer section 30 may have any suitable construction. In the embodiment illustrated, it comprises a tipple frame 36 journaled on a shaft 38. The latter shaft is journaled on frame 34, and has pulleys 28 training belts 26 fixed thereto. Journaled on tipple frame 36 are pulleys such as pulley 40, training one set of ends of laterally spaced conveyer belts of the tipple conveyer section, such as belt 42. The conveyer belts are trained at their other set of ends over pulleys secured to shaft 38 similar to pulley 28. Thus, the belts 42 are rotated conjointly with rotation of belts 26.

For shifting the tipple conveyor section between its low-

ered and raised positions, a double-acting ram or jack 44 is provided, having its rod end pivotally connected to a crank member 46, the latter in turn being connected to the tipple frame through a link 48. Extension of ram 44 produces rotation of the crank member in a counterclockwise direction in FIG. 2, with lowering of the tipple conveyor section, whereas contraction of the ram operates to raise the tipple conveyor section into the position shown in solid outline in FIG. 2.

10 Conveyor section 32 comprises two levels of conveyor belts, referred to herein as a lower level of belts (indicated at 50) and an upper level of belts (indicated at 52).

Describing first the lower level of belts 50, this comprises plural belts 54 spaced laterally from each other across the conveyor. Each belt is trained over pulleys, such as pulleys 56, 58 and 60 illustrated in FIG. 2. Pulleys 56 for the various belts 54 are secured to a transverse shaft 62, and in a similar manner, pulleys 58 and 60 for the various belts are secured to transverse shafts 64, 66. 15 Shafts 62, 64, 66 are journaled on stationary portions of frame 34. As will hereinafter be described, means is provided for rotating shaft 66 under power, in such a way that the belts are caused to move conjointly, with their upper runs moving from left to right in FIG. 2.

20 As can best be seen in FIG. 2, the upper runs of belts 54 adjacent the feed end of conveyer section 32 incline upwardly, and after passing pulleys 58 they extend in a substantially horizontal plane. Upper level of belts 52 is provided to flatten out veneer sheets traveling over the 25 horizontal expanses of belts 54. This assures that the sheet may pass easily through mechanism (to be described) which is operable when actuated to eject pieces to one side or to the other of the apparatus.

30 The upper level of belts comprises plural belts 68, one disposed over each belt 54, trained at opposite sets of ends over pulleys 70, 72. Pulleys 70 are secured to a shaft 74, and pulley 72 to a shaft 76, and these shafts in turn are journaled on frame 34. As will be described, during operation of the apparatus, shaft 76 is rotated under power, in a direction to cause the lower runs of these belts to travel from left to right in FIG. 2.

35 Explaining now the drive means for belts 54, 68, suitably mounted on frame 34 adjacent one side of the apparatus is a motor means, preferably an electric motor 80, having an output shaft 82. Output shaft 82 has a sprocket 84 secured thereto, which engages a drive chain 86. Chain 86 is also trained over a sprocket 88 secured to shaft 76. On energizing of the motor, sprocket 88 is rotated, and with it shaft 76 and the pulleys connected thereto. Drive 40 is transmitted from shaft 76 to shaft 66 (and the pulleys connected to shaft 66) by meshing gears 90, 92 secured to the respective shafts.

45 In operation of the apparatus, with the tipple conveyer section in its raised position, veneer sheets travel up the conveyer section and into the sorting station between levels of belts 50 and 52. In the event that it is desired to eject 50 a piece of veneer from a series of pieces traveling between the various belts, one of a pair of ejector means or mechanisms in the sorting station is actuated, and upon 55 its actuation the piece of veneer is thrown off to one side of the apparatus.

55 More specifically, and with particular reference to FIG. 3, adjacent one side of the apparatus, and operable when actuated to engage one end of a veneer piece and throw it off to one side, is an ejector means or mechanism indicated generally at 100. Adjacent the opposite side of the apparatus, and also operable to throw off a veneer piece when actuated, is another ejector means or mechanism 102. 60 Each ejector means may be actuated independently of the other. Each is constructed in a novel manner, whereby the end of a veneer piece is first grabbed, and the veneer piece is then shifted laterally, and finally thrown clear of the apparatus. The two ejector means are similar, and thus only one of them will be described in detail.

70 Considering in particular ejector mechanism 100, at 110

and 112 are indicated a pair of opposed pinch rollers or roller mechanisms, mounted with one vertically above the other. Roller mechanism 110 may comprise a series of rubber tired wheels 114 spaced laterally from each other and secured to a shaft 116. Similarly, roller mechanism 112 may comprise a series of rubber tired wheels 118 laterally spaced from each other and secured to a shaft 120.

Each roller mechanism is rotatably mounted in the apparatus, for rotation about a horizontal axis extending longitudinally of the conveyer means. Each is also shiftable vertically. Thus, shaft 116 of roller mechanism 110 carrying wheels 114 is journaled at its ends in crank members 122, and these crank members are pivotally mounted, as at 126 in frame 34, for pivotal movement about a horizontal longitudinally extending axis. With roller mechanism 110 in the position shown in solid outline in FIG. 3, bottom surface portions of the mechanism, i.e., the bottom surfaces of wheels 114, are below the plane of the bottom of belts 68, and in position to contact veneer pieces lying on belts 54. On pivotal movement of crank members 122 in a clockwise direction in FIG. 3, the roller mechanism is raised to the position shown in dashed outline, where the bottom surfaces of the wheels are above the plane of the bottoms of the belts, and out of the way of veneer pieces traveling thereunder.

Shaft 128 of roller mechanism 112 is journaled on crank members 128 pivoted on frame 34 at 130. In the position shown in solid outline, the upper surfaces of wheels 118 (or upper surface portions of the roller mechanism) are in position to contact with the underside of veneer pieces carried on belts 54. On pivotal movement of the crank members in a counterclockwise direction, the roller mechanism is shifted downwardly, to place the upper surfaces of the wheels below the top of belts 54.

Crank members 122 and crank members 128 are pivotally interconnected, as at 132. Further, shaft 126 is connected through a link 133 to the rod end of a double-acting ram or jack 134. The connection is such that on contraction of the ram, crank members 122, 128 are swung in such a manner as to separate the roller mechanisms and place them in their out of the way, or inoperative position. On extension of the ram, the roller mechanisms are moved toward each other, into their operative position. The ram or jack constitutes a means for actuating ejector means or mechanism 100, to place it in a position where it will initiate side movement of a piece of veneer.

Roller mechanisms 110, 112 are adjacent the side but inwardly of the path of travel of veneer pieces on the conveyer. Spaced adjacent but outwardly of the path of travel of veneer pieces are a pair of opposed pinch rollers or roller mechanisms, indicated at 140, 142. These pinch rollers are spaced close enough to roller mechanisms 110, 112, so that they will contact a piece of veneer shifted before the same moves free of rollers 110, 112. Pinch rollers 140, 142 thus function to draw a veneer piece outwardly that has already been shifted somewhat to the side, and finally to throw such a veneer piece endo and clear of the apparatus, where it may be collected in a pile.

Bottom roller mechanism 142 may comprise a cylinder on a shaft 141 journaled on frame 34 for rotation about an axis that parallels the rotation axes of roller mechanisms 110, 112. Upper roller mechanism 140 may comprise a similar cylinder on a shaft 143, journaled on pivoted arms 146 that are journaled on frame 34. By providing the pivot mounting for the upper pinch roller 140, it may move up and down to take care of veneer pieces of different thicknesses. The weight of the pinch roller is sufficient to cause the same firmly to grip a veneer piece when the same passes between the two pinch rollers.

In operation of the machine, the various roller mechanisms ordinarily are rotated under power and continuously. The motor drive is illustrated best in FIGS. 3 and 4. Specifically, at 148 is indicated motor means, preferably

pulley 152. Mounted on shafts 116, 120, 141, 143 are an electric motor, having an output shaft 150 secured to a pulleys 154, 156, 158 and 160, respectively. A belt 162 trained over the various pulleys operates to transmit drive from output shafts 150 to the pulleys secured to the various shafts. At 164 there is indicated an idler pulley, training the belt between pulleys 152, 154. On energizing of the motor, the various pulleys rotate in the direction indicated by the arrows in the drawings.

10 Ejector mechanism 102, as already explained, is similar to ejector mechanism 100 already described. Thus, it comprises a first set of roller mechanisms 172, 174 that may be shifted toward and away from each other, in order to grip or to release a veneer piece. Also part of the ejector mechanism are roller mechanisms 176, 178, 15 that function to throw veneer laterally completely free of the apparatus and into an appropriate collecting pile. At 180 there is indicated a double-acting fluid ram or jack, provided for shifting roller mechanisms 172, 174 between operative and inoperative positions. Ram or jack 180 20 may be actuated independently of ram or jack 134 of ejector mechanism 100.

Describing the drive for rollers 172, 174 and 176, 178, at 182 there is indicated an electric motor connected by 25 a belt to the various rollers. Motor 182 ordinarily is running constantly.

Completing the description of the sorting station, at 190 (see FIGS. 2, 3, and 5) is indicated a stop means, which may take the form of a pair of abutments 191, 192 secured to a bar 194. The abutments, in the raised or 30 operative position of the stop means, are in the path of travel of a veneer piece supported on belts 54. The abutments are aligned transversely of the apparatus, and when a veneer piece comes in contact therewith, the abutments 35 function to line up the lead edge of such a veneer piece and prevent its further forward travel.

Means is provided for shifting the stop means up and down between the raised position shown in solid outline in FIG. 5 and the lowered position indicated in dashed outline. This means comprises double-acting rams or jacks 196, mounted with their cylinder ends secured to frame 34 and with their rod ends connected to bar 194 so that on extension of the rams the bar is raised and on contraction the bar is lowered.

45 During normal operation of the apparatus, conveyer means 10, comprising section 10c and branches 10a and 10b, is driven at a somewhat faster speed than conveyer section 22 feeding clipper 20. Because of this, veneer sheets traveling on conveyer means 10 are spaced apart. The spacing enables a sheet to be ejected before a succeeding sheet enters the sorter.

If desired, a processing line may be provided where 50 tipple conveyer section 30 is shifted for successive sheets alternately first to its raised and then to its lowered position. Sorting stations then in each branch may be provided for sorting veneer sheets, with each branch having a sorting station for each type of veneer encountered. In this organization, a greater amount of time may be 55 permitted the sorting operation, since only alternate pieces travel down any one conveyer branch.

The operation of the apparatus should be clear from the above description. Veneer on traveling down conveyer section 22 is clipped and graded, as determined by an operator in station 24. Thence, after traveling down conveyer section 10c, a veneer sheet may travel either 60 forwardly on the upper branch 10a, or on the lower branch 10b, depending upon the setting of tipple conveyer section 30. Upon traveling into a sorting station, such as stations 12, 14, 16, and 18 (such stations being 65 similar to the one just described) removal of a veneer piece results from ejecting the piece if one of the ejector mechanisms therein is actuated. Removal is by ejecting the veneer piece either to one or the other side of the apparatus, depending upon the ejector mechanism actuated.

With the stop means lowered in a sorting station, a veneer piece travels through the station and into the next sorting station.

The apparatus can handle relatively thin sheets without damage. Sheets when they are ejected are thrown off endo, and by means which positively clears the path of the conveyer. Upon dropping into a pile, a sheet is subjected to stresses that tend to bend it transversely of its length, which is across the grain of the sheet and the type of stressing the sheet is best able to withstand.

Since a separate motor is provided for rotating the rollers of each ejector mechanism, there is no need for reversing a motor, or stopping its operation.

Veneer sheets leaving the clipper travel straight forwardly, in a direction extending transversely of their length. Thus, there is no turning of the sheets or change in their direction of travel. A relatively compact sorting line results, since collections may be made on both sides of the sorting line.

While a particular embodiment of the invention has been described, it is appreciated that various changes may be made in the parts and/or their organization. It is desired not to be limited to the specific embodiment disclosed, but to cover all modifications and variations that would be apparent to one skilled in the art, and that come within the scope of the appended claims.

It is claimed and desired to secured by Letters Patents:

1. In sorting apparatus, conveyer means for moving elongated sheets in a direction extending transversely of their length along a path and into a sorting station, said conveyer means in said sorting station defining a substantially horizontal support plane for sheets, and ejector mechanism for removing sheets in said sorting station and ejecting them laterally to one side of said conveyer means, said ejector mechanism comprising a power-driven roller adjacent and inwardly of one side of said path rotatable about an axis extending longitudinally of said path and with a work-contacting surface spaced vertically from said support plane of said conveyer means so as to be out of contact with sheets deposited thereon, means for shifting said roller vertically and relative to sheets on said conveyer means in said sorting station to an operative position where its work-contacting surface engages such sheets, and a set of opposed pinch rollers adjacent and laterally outwardly of said one side of said path mounted with the rollers of the set substantially paralleling said first-mentioned pinch roller and in a position to receive sheets shifted laterally thereinto by said first-mentioned roller, at least one of said rollers of said set of pinch rollers being power driven.

2. In sorting apparatus, conveyer means for moving elongated sheets in a direction extending transversely of their length along a path and into a sorting station, said conveyer means in said sorting station including a lower level of conveyer belts substantially paralleling said path for supporting the underfaces of such sheets and an upper level of conveyer belts positioned over the lower level of belts for holding the sheets flat on the lower level of belts, and ejector means for removing sheets in said sorting station and ejecting them to one side of said conveyer means, said ejector means comprising a pair of power-driven pinch rollers adjacent and inwardly of one side of said path and rotatable about parallel axes extending longitudinally of said path, said pair of rollers including one roller between two belts of said lower level of belts and one roller between two belts of said upper level of belts, said pinch rollers having work-contacting surfaces spaced above and below sheets traveling in said path so as to be out of contact therewith, means for shifting at least one of said pinch rollers toward the other to place the two rollers in contact with opposite faces of sheets in said station, and a set of opposed pinch rollers adjacent and outwardly of said one side of said path mounted with the rollers of the set substantially paralleling the

rollers of said pair of pinch rollers and positioned to receive sheets shifted laterally by said pair of pinch rollers, at least one roller of said set being a power-driven roller.

3. Apparatus comprising means for supplying veneer with the veneer moving along a course and in a direction extending transversely of the grain therein,

elongated conveyer means defining a path which is aligned with and a continuation of said course operable to transport veneer sheets with the grain of the sheets extending transversely thereof, and plural sorting stations along the length of said conveyer means for sorting veneer sheets and operable to sort sheets by shifting them laterally to one side of said path,

each of said sorting stations comprising a shiftable stop means having an inoperative position where it is out of the way of sheets traveling on the conveyer means and an operative position where it is in a position to engage the leading edge of a sheet in the sorting station and prevent its further forward travel, and a pair of ejector means disposed adjacent opposite sides, respectively, of said path,

each of said ejector means including pinch roll mechanism substantially paralleling the path defined by the conveyer means operable on actuation to engage veneer sheets across their grain thus to shift the veneer sheets to one side of said path with the veneer sheets then traveling in the direction of their grain, said conveyer means in each sorting station comprising a lower level of conveyer belts for supporting the veneer sheets in the station and an upper level of conveyer belts positioned over tops of sheets in the station, said upper and lower level of conveyer belts forming the top and bottom of a narrow chamber for receiving sheets with said chamber having width and length dimensions extending in a substantially horizontal plane,

said pinch roll mechanism of each ejector means comprising a first pair of oppositely disposed pinch rollers disposed adjacent and laterally inwardly of a side of said path defined by the conveyer means with one roller above and one roller below said chamber defined by said belts, and a second pair of oppositely disposed pinch rollers disposed adjacent but laterally outwardly of said side of said path with one above and one below the path, at least one roller of each pair of pinch rollers being power driven, the pinch rollers of the first-mentioned pair of pinch rollers being shiftable between an inoperative position where their surfaces are spaced above and below said chamber and an operative position where said surfaces project into said chamber and engage opposite sides of a sheet therein.

4. Sorting apparatus comprising a lower level of substantially parallel conveyer belts defining a substantially horizontal support plane for sheets, and upper level of substantially parallel conveyer belts defining a substantially horizontal hold-down plane paralleling said support plane, said upper level of belts being operable to hold sheets flat on said lower level of belts, and side ejector mechanism for shifting sheets laterally of said belts, said side ejector mechanism comprising a first set of rollers including a roller between two belts of said lower level of belts mounted for rotation about an axis substantially paralleling the belts, and another roller between two belts of said upper level of belts mounted over the first-mentioned roller for rotation about an axis paralleling the rotation axis of the first-mentioned roller, the top of said first-mentioned roller being below the top of said support plane and the bottom of the second-mentioned roller being above said hold-down plane, means for shifting said first-mentioned roller upwardly to place the top below the top of said support plane and for shifting said second-mentioned roller downwardly toward the other roller

to place its bottom below the base of said hold-down plane, said rollers of said first set upon being shifted toward each other being operable to grab a veneer sheet along zones between adjacent belts in the two levels of belts while holding the sheets between the planes defined by said first and second level of belts, and a second set of opposed pinch rollers adjacent and laterally outwardly of the belts in said first and second level of belts, said rollers of said second set substantially paralleling said rollers of said first set of rollers, said second set of rollers being in a position to receive sheets shifted laterally thereinto by said first set of rollers, at least one of the rollers of said second set of rollers being power driven.
